Attorney

UNITED STATES PATENT OFFICE.

ALBERT J. LAHMER, OF TORONTO, ONTARIO, CANADA, ASSIGNOR OF ONE-HALF TO
GEORGE WILLIAM KNOWLING, OF DETROIT, MICHIGAN.

SANITARY CLOSET-SEAT COVER.

Application filed November 11, 1922. Serial No. 600,253.

To all whom it may concern:

Be it known that I, ALBERT J. LAHMER, a subject of the King of Great Britain, residing at Toronto, in the county of York,

5 Province of Ontario, Dominion of Canada, have invented certain new and useful Improvements in Sanitary Closet-Seat Covers, of which the following is a specification, reference being had therein to the accompanying drawings.

This invention relates to a closet seat cover and one of the objects of my invention is to provide a cover that may be easily and quickly mounted on the seat or upper end of 15 a water closet bowl and automatically removed therefrom when the bowl is flushed by water, the cover being made of a perishable material that will be eventually destroyed or disintegrated by the water, without 20 clogging a sewer or other outlet pipe.

Another object of this invention is to provide a health protecting cover for a closet seat which may be disposed of without the user of the cover touching the same, thus 25 reducing to a minimum the spread of disease by contagion. In order that this may be accomplished the cover has means within the path of flushing water adapted to be washed away by the water and drag the 30 cover with it.

A further object of my invention is to provide a new article of manufacture in the form of a closet seat cover cut, stamped or otherwise produced from tissue paper or 35 other flexible material, the cover being slit-ted to afford a central portion that may be depressed to provide a drag member which will serve as a baffle, a receptacle, and as a means of withdrawing the article from the 40 seat on which it is placed.

The above and other objects are attained by a health protecting device that is inexpensive to manufacture, easy to install, applicable as an advertising medium, and 45 highly efficient for the purposes for which it is intended.

Reference will now be had to the drawing, wherein

Figure 1 is a plan of one form of a sanitary seat cover in accordance with my invention;

Fig. 2 is a perspective view of the same;

Fig. 3 is a plan of another form of cover;

Fig. 4 is a perspective view of the same, 55 and

Fig. 5 is a perspective view of a closet bowl, partly broken away, and partly in section, showing a cover in a useful position on the bowl.

Reference will first be had to Figs. 1 and 60 2 showing an oval cover 1 having an oval opening 2, said cover conforming in outline to the seat or upper portion 3 of a bowl 4 having a basin or trap 5 adapted to be flushed by water. The cover 1 can be made 65 from tissue paper or any suitable flexible or perishable material. It may be cut and stamped from a paper sheet and in providing the opening 2 the paper sheet is cut or stamped to form a shield or tongue 6 at 70 the front edge of the opening 2, said shield or tongue being substantially semi-circular and adapted to be bent downwardly from the opening 2 on the dash line 7 shown in Fig. 1, so that the shield or tongue will 75 extend into the opening 8 of the bowl seat 3 and prevent a body sitting on the cover 1 from contacting with the front wall of the seat opening 8.

Suitably attached to the cover 1, at the 80 marginal edges of the opening 2, are the upper ends 9 of a plurality of foldable stirrup or bail shaped straps 10 which are preferably placed at a right angle to each other so that the bottom or straight portions 85 11 of said straps may cooperate in supporting a drag member 12 made from the piece of material removed from the opening 2. This drag member is adapted to serve as a baffle or receptacle and may be adhesively connected to the strap and said strap similarly connected to the cover 1, so that 90 said elements are articulated, either when extended as shown in Fig. 2 or when the straps 10 are folded with the drag member 95 12 in proximity to the cover.

Reference will now be had to Figs. 3 and 100 4 showing a cover which has integral straps and a drag member. In cutting a sheet of paper to provide the cover 1, said sheet of paper is provided with sets of circumferentially disposed slits 13, 14 and 15 with the slits 13 and 14 connected by radially disposed slits 16, which in turn communicate with the slits 15 at one end of the cover, while the slits 15 at the opposite end of the 105 cover communicate with a semi-circular slit 17 providing the shield or tongue 6. Now it is only necessary to depress the central portion of the cover 1 to provide the drag 110

2
member 12. As the central portion of the cover is depressed the slitted portions of the cover open or unfold, as shown in Fig. 4 to form the straps 10 which support the drag member 12 below the plane of the cover 1. This manner of forming the cover provides a flat structure conducive to packing or dispensing by a vending machine.

In either form of my invention the cover 1 can be easily placed on the seat 3 and the drag member 12 depressed until it is suspended from the cover in proximity to the water in the basin or trap 5. The cover will be held in place by the occupant of the bowl and the drag member 12, serving as a receptacle, will receive fecal matter.

When the seat is unoccupied and the bowl flushed the drag member 12 will serve as a baffle to the extent of causing the water 20 to carry it off into the sewer or outlet pipe and since the drag member is articulated with the cover 1, said cover will be pulled through the opening 8, off of the seat 3 and be dragged into the path of the water 25 to be carried off in the sewer or outlet pipe. The drag member also serves as a baffle when the seat is occupied by preventing water or other matter within the trap or basin from being splashed on the body occupying the 30 seat.

From the foregoing it will be observed that after the cover is placed on the seat it need not be handled and since the flesh

is prevented from contacting with the closet seat there is no danger of a contagious disease spreading from one person to another. It is thought that other advantages will be obvious without further description, and while in the drawing there are illustrated the preferred embodiments of my invention, it is to be understood that the construction may be varied as to size, shape and material, without departing from the appended claims.

What I claim is:—

1. As a new article of manufacture, a closet seat cover made of a single piece of material cut to provide concentric slits affording a plurality of extensible straps and a drag member which may be depressed and supported by said straps at such points as to sustain a load on said drag member, said straps by virtue of said slits being tearable intermediate the ends thereof to part when the load becomes too great.

2. A new article of manufacture as called for in claim 1, wherein the concentric slits melt radial slits and a semi-circular slit, said semi-circular slit affording a shield between the upper ends of two of said straps.

In testimony whereof I affix my signature in presence of two witnesses.

ALBERT J. LAHMER.
